EDWIN G. FRANCK, OF DETROIT, MICHIGAN, ASSIGNOR TO HUTCHINS CAR ROOFING COMPANY, OF DETROIT, MICHIGAN, A CORPORATION OF DELAWARE

CAR ROOF

Application filed May 25, 1931. Serial No. 539,942.

The invention relates to car roofs designed for application to open cars of the gondola type when said cars are used for carrying loads requiring protection from the weather. 5 It is the primary object of the invention to obtain a construction which may be easily applied to or removed from the car and which also facilitates loading and unloading. To this end the invention consists in the construction as hereinafter set forth.

In the drawings:

Figure 1 is a plan view of the roof;

Figure 2 is a side elevation of a portion of the roof;

15 Figure 3 is a cross section therethrough;

Figure 4 is a longitudinal section through adjacent roof sections.

Figure 5 is a section on line 5—5 of Figure 1.

20 As my improved roof is designed for only temporary use, it is desirable to reduce the weight to the minimum, thereby facilitating easy removal and replacement. At the same time it is necessary to provide sufficient strength not only to effectually protect the contents of the car but also to permit the travelling of trainmen thereover. To accomplish such results I have constructed the roof of flanged roofing sheets arranged alter-

25 nately in spaced planes and with their flanges riveted to each other so as to produce a truss. This dispenses with the necessity of carlines or other independent transversely extending reinforcing member. The roof is also formed 30 in a plurality of sections so that by removing one or more of said sections access is provided for loading and unloading.

In detail, A are the roofing sheets of the lower plane and B the roofing sheets of the 40 upper plane alternating with each other and extending transversely from eaves to eaves. The plates A are provided at their opposite edges with upturned flanges C and the plates B are similarly provided at their edges with 45 downturned flanges D overlapping the flanges C. These flanges are then riveted to each other forming of the two plates a Z-shaped cross section. At the eaves the flanges C and D are turned into the plane of the sheets and 50 are then bent downward in overlapping rela-

tion as indicated at E to form the depending eaves flanges. The end sheet A' also has a downturned end flange F extending completely across from side to side of the car. These downturned flanges E and F are 55 reinforced by angle bars G having their horizontal flanges G' extending in a common plane both on the sides and at the end of the car and adapted to rest on the angle flange H which forms the top of a gondola 60 car. The plates A and B are fashioned to slope from the ridge towards the eaves and at the ridge are reinforced by a channel shaped ridge pole I. The saddle members J of angle construction are riveted to the 65 overlapping flanges C and D above the ridge and these saddles support running boards H'. Thus the entire structure is one which is exceedingly light and which therefore may be easily lifted on or off the car.

70 As has been stated, the roof is formed of a plurality of sections which may be independently removed or replaced. These sections adjacent to each other are provided with upturned flanges K which are reinforced 75 by angle bars L. Transverse caps M embrace these upstanding flanges and are clamped upon the sheets by pins N. The cap M also supports a short running board section H² which is intermediate the running boards H' of the main sections and to further support this section H' it extends over and rests upon extensions of the saddles J beyond the ends of the boards H'. 80

To secure the roof upon the car, any suitable clamping means may be provided but as shown this comprises hinge brackets O secured to the depending flanges E and bent clamping levers P pivoted to said brackets and engaging the under side of the flanges H on the car. Clamping bolts Q passing through the levers P and flanges E serve to draw the former into tight engagement with the angles H. 85

In use the car may be first loaded and the roof sections then applied thereto, or all of the sections excepting one may be first applied and the car loaded through the remaining opening. 90 95 100

What I claim as my invention is:

1. A roof for gondola type open cars comprising a series of rigidly connected roofing sheets extending from eaves to eaves and pitched from ridge to eaves, depending flanges from the eaves ends of said sheets and across the end of the car, flanges extending laterally inward from said depending flanges arranged in the same plane at eaves and at the car end to rest upon the upper edge of the gondola body, and means for clamping said flanges to said body.
2. The combination with a gondola car having an outwardly extending reinforcing flange at the upper edges of its sides and ends, of a roof therefor comprising roofing sheets extending from eaves to eaves and rigidly secured to each other, said sheets being pitched from ridge to eaves, depending flanges at the eaves ends of said sheets and at the ends of the car, flanges extending laterally inward from said depending flanges arranged in the same plane and adapted to rest upon the outwardly extending flanges of the gondola car and means secured to said depending flanges for clamping beneath said reinforcing flanges of the car to hold said roof thereto.
3. The combination with a gondola car having outwardly extending reinforcing flanges at the upper edges of its sides and ends, of a roof for said car comprising a series of roofing sheets extending from eaves to eaves and alternately in spaced planes, said sheets being pitched from ridge to eaves and having oppositely extending flanges overlapping and rigidly secured to each other, depending flanges on said sheets at the eaves arranged substantially in the same plane and spaced from the sides of the car, a depending flange from the outer end of the end sheet, flanges extending inwardly from said depending flanges arranged in the same plane and adapted to rest upon the upper flanged edge of the gondola car, and clamping means engaging the under side of the flange of the car to secure the roof thereto.

In testimony whereof I affix my signature.
EDWIN G. FRANCK.
